(57) **CLAIM**

The ornamental design for a rotation wheel extension, as shown and described.

DESCRIPTION

FIG. 1 is a perspective view of a rotation wheel extension according to the present invention.

FIG. 2 is a right side view of the rotation wheel extension of FIG. 1.

FIG. 3 is a left side view of the rotation wheel extension of FIG. 1.

FIG. 4 is a rear view of the rotation wheel extension of FIG. 1.

FIG. 5 is a front view of the rotation wheel extension of FIG. 1.

FIG. 6 is a top view of the rotation wheel extension of FIG. 1; and,

FIG. 7 is a bottom view of the rotation wheel extension of FIG. 1.

The broken lines shown in FIG. 7 illustrate portions of the rotation wheel extension that form no part of the claimed design.
